US0D1094415S

(12) **United States Design Patent** (10) **Patent No.:** **US D1,094,415 S**
(45) **Date of Patent:** **** Sep. 23, 2025**

(54) **DISPLAY SCREEN WITH A GRAPHICAL USER INTERFACE**

(71) Applicant: **Aristocrat Technologies, Inc.**, Las Vegas, NV (US)

(72) Inventors: **David Marsh**, Charlottesville, VA (US); **Daniel Marston**, Reno, NV (US); **Brian Prince**, Reno, NV (US)

(73) Assignee: **Aristocrat Technologies, Inc.**, Las Vegas, NV (US)

(**) Term: **15 Years**

(21) Appl. No.: **29/939,291**

(22) Filed: **Apr. 25, 2024**

(51) LOC (15) Cl. **14-04**

(52) U.S. Cl.

USPC **D14/485**

(58) **Field of Classification Search**

USPC **D14/485-495**

CPC **H04M 1/724-7248; G06F 3/048; G06F 3/0482; G06F 3/04817; A63F 13/00; A63F 1/00; A63F 3/06; A63F 5/00; A63F 1/04; G06Q 50/34**

(57) **CLAIM**

The ornamental design for a display screen with a graphical user interface, as shown and described.

DESCRIPTION

The sole FIGURE is a front view of a display screen with a graphical user interface showing the claimed design.

The broken lines illustrate the display screen and portions of the graphical user interface and form no part of the claimed design.

1 Claim, 1 Drawing Sheet
